UNITED STATES PATENT OFFICE

FRANK BOLHUIS, OF HOLLAND, MICHIGAN

CUPBOARD UNIT CONSTRUCTION

Application filed May 5, 1930. Serial No. 449,893.

This invention relates to a cupboard or kitchen cabinet construction, the primary object and purpose of which is to provide a construction having upper and lower cabinet sections spaced from each other, with an intervening table section between which a sink may be located, the sink being supported at its ends by the inner sides of the lower cabinet sections and having its outturned upper edges received in a rabbeted recess at the lower side of the table and around an opening in the table below which the sink is disposed; and to provide a simple and very practical construction whereby the intervening table section may be inserted or removed, this being of value in the installation of the cabinet in the first instance and for removal at any time for repair, inspection or replacement should it at any time become necessary or desirable.

The invention is fully described in the following description, taken in connection with the accompanying drawings, in which,

Fig. 1 is a front elevation of the kitchen cabinet or cupboard construction of my invention.

Fig. 2 is a fragmentary longitudinal vertical section through the table, the sink and the adjacent parts of the lower cabinet sections.

Fig. 3 is a transverse vertical section showing the manner in which the intermediate table section of the structure may be inserted or removed.

Fig. 4 is a view similar to that shown in Fig. 3 showing the intermediate table section installed and secured in place, and

Fig. 5 is a fragmentary vertical section substantially on the plane of line 5—5 of Fig. 4.

Like reference characters refer to like parts in the different figures of the drawings.

In the cabinet or cupboard structure illustrated, two lower sections 1 are provided which are spaced apart a distance from each

other. These cabinet sections rest on the floor and between them at their upper ends a sink 2, provided with outturned horizontal flanged edges 3, is disposed and supported at its ends by the flanges resting upon horizontal supporting bars 4 permanently connected to the inner sides of the sections 1 at the upper ends thereof.

The cabinet includes two spaced apart upper sections 5 located a distance above the upper ends of the lower sections 1 and when installed are permanently secured to a wall or other support, and between the upper sections 5 at their backs, a window or panel 6 may be disposed which may carry a mirror or any other desired article. The sections 1 and 5 may be of any suitable construction partitioned to receive various kitchen utensils, the interior construction thereof being no part of the present invention. At the underside and back of the upper sections 5 a horizontal rail 7 is located which may be secured permanently either to the wall or to the sections. This rail has any suitable jointed connection indicated at 8 with the underside and rear portions of the upper sections 5 and at its lower portion is recessed at its front side to provide a downwardly extending tongue 9 which extends the full length of the bar 7. In addition other bars 7a identical in cross section and having downwardly extending tongues 9a are connected at the bottoms and at the outer edges of the upper sections 5, their front ends terminating a short distance back of the fronts of said sections 5 as best shown in Fig. 3.

The intermediate or table section which is to go between the lower sections 1 and the upper sections 5 comprise a flat horizontal table 10 of a length to extend from the outer side of one section to the outer side of the other and form a top or cover for the upper ends of the lower sections 1. Where it passes over the sink 2 an opening 11 is made for access to the sink, and around this opening

at the under side of the table 10 a rabbeted recess 1a is made to receive the outturned flanges 3 of the sink. The table may be of any suitable material, and in practice it preferably comprises a wood bed with a covering of phenolic material at its upper side and edges which is impervious to moisture.

At the rear edge of the table is a vertical back 12 permanently secured thereto to bear 10 against the wall and at each end of the back are forwardly extending vertical ends 13, the inner sides of both the back and ends 12 and 13 being also suitably covered with sheets of phenolic material. The upper edges of the 15 back 12 and the ends 13 are recessed for their full lengths at their outer sides thereby providing upwardly extending tongues 14 at their inner sides so that when the table section is installed in place over the lower sections 1 and under the upper sections 5 the tongues 9 and 9a on the bars 7 and 7a make an overlapping joint with the tongues 14 on the back and ends 12 and 13 of the intermediate table section.

25 It will be noted, referring to Fig. 4, that the height of the back 12 and of the ends 13 is such that when the table 10 is located over the lower section 1 and the flanges 3 of the sink 2 received in the recess 11a at the under 30 side of the table, there are spaces greater than the thickness of said flanges 3 between the upper edges of the tongues 14 and the adjacent lower side of the recess in the bars 7 and 7a into which they extend and corresponding spaces between the lower edges of the tongues 9 and 9a and the upper sides of the recesses in the back 12 and ends 13 in which said tongues are seated. This permits the table section to be moved over the 40 upper sides of the flanges 3, so that the table section comprising the table 10, the back 12 and the ends 13 may be bodily inserted or removed for installation purposes or for removal after the installation has once been 45 made, it being possible to lift the intermediate table section bodily upward so as to bring the lower side of the table 10 above the upper sides of the flanges 3, due to the spaces above the tongues 14 and below the tongues 9 and 9a, as best shown in Fig. 4.

50 After the table section is in place between the lower cabinet sections 1 and the upper cabinet sections 5, the open joints between the bar 7 and the back 12 and between the bars 7a and the ends 13 are covered by covering strips 15 and 16 which are detachably connected in place by means of screws 16 passing therethrough into the bars 7 and 7a. The installation is completed by vertical covering bars or strips 17 located against the front edges of the ends 13 and extending a short distance above the upper edges thereof so as to completely cover the front ends of the bars 7a as well as the front edges of the 55 ends 13.

This construction of cabinet or cupboard is one particularly easy to install in a home. The cabinet sections 1 and 5 may be manufactured complete at the factories, the bars 7 and 7a are likewise of standard form and 70 may be sawed to required lengths, while the table sections comprising the horizontal table 10, the back 12 and the ends 13 may also be made in either standard or special lengths as may be required. The installation consists in 75 properly locating the lower sections 1 and positioning and mounting the sink 2 between them; locating and securing the upper cabinet sections 5 and the bars 7 and 7a associated therewith against the wall, then inserting the intermediate table section in place by sliding it over the upper sides of the flanges 3 of the sink, and then attaching the finishing strips or members 15, 16 and 17 by means of removable screws. If at any time it is 80 desired to remove the intermediate table section for inspection or repair or replacement it is very quickly and easily accomplished by merely removing the various finishing and 85 retaining strips 15, 16 and 17. When the finishing and retaining strips 15, 16 and 17 are secured in place the intermediate table section is locked against movement and serves 90 at the same time to hold the sink in permanent and secure relation with respect to the remainder of the cabinet.

This construction has proved very useful, practical and serviceable. The invention is defined in the appended claims and is to be considered comprehensive of all forms of 100 structure coming within their scope.

I claim:

1. In a construction of the class described, two spaced apart lower cabinet sections, a sink having outturned flanges around its upper edges supported on and extending between the upper ends of said sections, a cabinet structure located above said lower cabinet sections and sink and spaced therefrom, an intermediate table section comprising a horizontal table, a vertical back and vertical ends attached to said back and table, said table having an opening over the sink and being recessed at its underside around said opening to receive the flanges of the sink, a rail disposed at the underside and rear portion of the upper cabinet structure substantially the full length of the table, end rails attached to the upper cabinet structure extending forward at right angles from the ends of the first rail, said rails at their underside and said back and ends of the intermediate table section at their upper edges being provided with overlapping tongue portions permitting an elevation of the intermediate table section a short distance greater than the thickness of the flanges of the sink, and covering strips detachably secured at the inner sides of said rails and extending over 110 115 120 125 130

the joints between the same and the back and ends of said intermediate table section.

2. A construction containing the elements in combination defined in claim 1, combined with covering and finishing members detachably secured to the front edges of the ends of said intermediate table section and extending upwardly above the upper edges thereof so as to cover the front ends of said end rails and the covering strips detachably secured at the inner sides thereof.

In testimony whereof I affix my signature.

FRANK BOLHUIS.
